[57] CLAIM

The ornamental design for a mid-range loudspeaker, as shown and described.

DESCRIPTION

FIG. 1 is a top and right side perspective view of a mid-range loudspeaker showing our new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a left side elevational view of a second embodiment of the mid-range loudspeaker illustrated in FIG. 1, the right side being a mirror image; and, FIG. 7 is a rear elevational view of the embodiment disclosed in FIG. 6.

The broken line showing of a base and speaker cover are environmental only and form no part of the claimed design.

The bottom of the loudspeaker is plain and unornamented.

The unillustrated views of the second embodiment are the same as the corresponding views of the embodiment disclosed in FIG. 1.
